UNITED STATES PATENT OFFICE.

BENJAMINE W. HEITZ, OF BRAINERD, MINNESOTA.

GRAIN-CAR DOOR.

Application filed May 31, 1922. Serial No. 564,730.

To all whom it may concern:

Be it known that I, BENJAMINE W. HEITZ, a citizen of the United States, residing at Brainerd, in the county of Crow Wing and State of Minnesota, have invented certain new and useful Improvements in Grain-Car Doors; and I do hereby declare the following to be a full, clear, and exact description of the invention, such as will enable others skilled in the art to which it appertains to make and use the same.

The present invention relates to grain car doors, and aims to provide a novel and improved permanent door structure for grain cars, to eliminate the use of the temporary doors made of boards nailed to the door frames for retaining the grain, sand or other material.

Another object is the provision of novel means for mounting double or a pair of doors to be disposed at an angle with one another when closed, for withstanding the pressure of the grain or material against same from within the car, and to provide a tight fit between the doors and between the doors and door frame, so as to avoid leakage, said mounting enabling the doors to be conveniently moved to open and closed positions.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is an outer elevation showing the doors in closed position.

Fig. 2 is an inner elevation with the doors closed.

Fig. 3 is a top plan view showing the doors in closed position, with the door frame shown in section.

Fig. 4 is a view similar to Fig. 3 showing, in full lines, the position of the doors when swinging them together or apart, and showing, in dotted lines, the doors swung into the car behind the side wall thereof out of the way.

Fig. 5 is a similar view showing the doors swung outwardly.

The doors 7 and 8 may be of wood, metal, or of composite construction, and such dou-

ble doors are jointly wider than the door opening, and the doors are hingedly mounted for swinging and shifting movement about different vertical axes. The hinge 60 mountings include flexible hinges having the leaves 9 secured to the inner sides of the doors at their opposite edges, leaves 10 secured to the inner sides of the door posts or jambs 11 of the door frame, and pairs of 65 intermediate leaves 12 hingedly connected with one another and with the leaves 9 and 10. The leaves 12 can be doubled or folded together, and provide for the shifting of the doors to different positions relatively to 70 the posts 11, those edges of the doors adjacent to the posts being capable of movement to different positions adjacent to and around the posts.

Vertical cleats or stops 13 are secured to 75 the posts 11 for the opposite edge portions of the doors to bear outwardly against, the leaves or links 12 straightening out as said edges of the doors are shifted outwardly against the cleats or stops 13, as seen in 80 Fig. 3.

The adjacent vertical edges of the doors have means to fit together, for preventing leakage, including a flange 14 extending at an obtuse angle from the free edge portion 85 of the door 8 to be disposed in the same vertical plane as the door 7 when the doors are in closed position, and a pair of strips 15 is secured to the free edge portion of the door 7 to provide a vertical groove 15' for receiving said flange 14, thereby providing a snug fit between the doors.

Each of the doors is provided at its lower end with a discharge or release opening 16 normally closed by an auxiliary door 17 95 hinged, as at 18, to the corresponding main door above the opening 16, for the outward and upward swinging movement of the auxiliary door to open position. Stops 19 are secured to the inner sides of the main doors 100 for preventing the inward swinging movement of the auxiliary doors when in closed position.

In using the doors, they are closed before the car is filled, and the doors are therefore 105 swung outwardly within the door opening, and by swinging the doors and shifting them relatively, as suggested in Fig. 4, doubling one or both of the hinged mountings, the flange 14 can be inserted in the 110 groove 15', and the doors are then shifted outwardly along the adjacent sides of the

posts 11 to the position as shown in Fig. 3, with the opposite vertical edge portions of the doors bearing outwardly against the stops 13 and the edges of the doors abutting the posts 11. The doors will assume an obtuse angle with one another, so as to converge inwardly from the door posts, as seen in Fig. 3, whereby to withstand great pressure from within the car, it being noted that the pressure against the inner sides of the doors will press the opposite edge portions of the doors tightly against the stops 13, and the doors tending to straighten out will thrust the opposite edges thereof tightly against the jambs or posts 11, to prevent leakage past the opposite edges of the doors, and to also transmit the pressure from the doors to the posts 11, in order to effectively resist the tendency for forcing the adjacent edges of the doors open outwardly. The links or leaves 12 permit the opposite edges of the doors to be swung and shifted to bear against the cleats or stops 13 and posts 11. Before filling the car, boards or cleats 20 are nailed or otherwise fastened on the door sill or floor along the lower ends of the doors to contact with the outer sides of the doors, and assist in preventing outward displacement of the doors under the pressure from the inside, and similar boards or cleats 21 can also be nailed or otherwise secured on the floor or deck behind the doors, to prevent accidental opening of the doors while the car is being filled. The boards or cleats 20 also extend across the auxiliary doors 17 to prevent them from being opened. The car is then filled by running the grain, sand or other material over the doors through a chute, or the like. The doors fitting together tightly and fitting against the jambs or posts 11 tightly, will prevent leakage past the vertical edges, and the cleats 20 and 21 will also prevent leakage under the doors, as well as holding the doors closed. In order to start the discharge of the material from the car, the cleats 20 are pried up and removed, which will permit the auxiliary doors 17 to swing open outwardly and upwardly, for the discharge of

the material through the openings 16. After the material has been sufficiently removed or loosened from behind the doors and the cleats 21 loosened, the doors can be swung and shifted inwardly, as seen in Fig. 4, to separate them, and the doors can then be swung outwardly, as seen in Fig. 5, for removing the remaining material from the car. After the car has been emptied, the doors can be swung inwardly behind the side wall out of the way, as seen in dotted lines in Fig. 4.

Having thus described the invention, what is claimed as new is:—

1. A door construction comprising door posts having stops, a pair of doors arranged when closed, at an angle with one another with their adjacent edges fitted together and their opposite edges abutting the posts and bearing against said stops, and means for mounting said doors on the posts for the swinging movement of the doors and for the shifting movement of their opposite edge portions along the adjacent sides of the posts to abut the posts and move against said stops. 75

2. A door construction comprising door posts having stops, a pair of doors arranged, when closed, at an angle with one another with their adjacent edges fitted together and their opposite edges abutting the posts and bearing against said stops, and means for mounting said doors on the posts for the swinging movement of the doors and for the shifting movement of their opposite edge portions along the adjacent sides of the posts to abut the posts and move against said stops, said means including pairs of hinge leaves between the doors and posts hingedly connected with one another and with the doors and posts and adapted to be doubled between said doors and posts. 90

In testimony whereof I have signed my name to this specification in the presence of two subscribing witnesses.

BENJAMINE W. HEITZ.
